UNITED STATES PATENT OFFICE.

GEORGE HENRY WHEARY, OF RACINE, WISCONSIN.

TRUNK LOCK.

Application filed June 13, 1921. Serial No. 473,536.

To all whom it may concern:

Be it known that I, GEORGE H. WHEARY, a citizen of the United States, and resident of Racine, in the county of Racine and State 5 of Wisconsin, have invented new and useful Improvements in Trunk Locks, of which the following is a description, reference being had to the accompanying drawings, which are a part of this specification.

10 This invention relates to improvements in trunk locks.

Trunks are oftentimes sent by express to their destination, and in shipping it is desirable to seal the lock to prevent surreptitious opening of the same. This has been found very difficult due to the shape of the ordinary trunk lock which does not permit securing a sealing wire thereto.

15 It is one of the objects of the present invention to overcome the before-mentioned objectionable features and provide a trunk lock having means whereby the lock may be easily wired and sealed in a very simple manner.

20 A further object of the invention is to provide a trunk lock having engaging portions which may be easily wired and sealed in a simple manner and with a minimum amount of material.

25 With the above and other objects in view the invention consists of the improved trunk lock and its parts and combinations as set forth in the claims, and all equivalents thereof.

30 In the accompanying drawing in which the same reference characters indicate the same parts in all of the views:

Fig. 1 is a front view of a portion of a trunk provided with the improved lock and 35 showing a seal connected thereto;

Fig. 2 is a sectional view thereof taken on line 2—2 of Fig. 1;

Fig. 3 is a sectional detail view taken on line 3—3 of Fig. 1; and

40 Fig. 4 is a sectional detail of the lock hinge.

45 Referring to the drawing the numeral 5 indicates the body of a trunk of any type, 6 the top cover and 7 the improved lock. Said lock comprises a plate 8 adapted to be secured to the trunk cover and which is provided with the hinged lock member 9. The lock portion 9' of the lock projects outwardly and is provided with transverse locking bolts 10 which lock against the edge 11 of the opening of the escutcheon plate 12

which is fastened to the body portion of the trunk. The plate 8 is also provided with locking tongues 13 which enter tongue recesses 14 formed in the escutcheon plate 12. 60

In order to automatically swing the locking member to open position coiled springs 15 encircle the hinge pin 16 of the lock member and the opposite ends of the springs bear against the plate 8 and the lock member 9, respectively. 65

The lock member 9 between the lock portion 9' and the hinge pin 16 is provided with a vertically extending slot 17 through which extends a post 18 having an eye 19 in its outer end. The inner end of the post is rigidly riveted to the escutcheon plate 12 above the lock opening and projects through the lock member slot a sufficient distance to position the eye of the post in front of the 75 lock member. A wire or staple 20 is extended through the eye and a seal member 21 of any construction desired is non-removably secured to the end portions of the wire or staple as shown in Fig. 1 and as the seal 80 is larger than the slot the lock cannot be opened with breaking the seal. As thus constructed and sealed it will be impossible to surreptitiously open the trunk without the knowledge of the owner or shipper. As 85 the part added to the lock is very small it is hardly noticeable and does not in any manner interfere with the ordinary use of the trunk.

From the foregoing description it will be 90 seen that the trunk lock is of very simple construction and is well adapted for the purpose described.

What I claim as my invention is:

1. A trunk lock, comprising a plate member having a keyed lock member hinged thereto and provided with an opening, an escutcheon plate engaged by the lock member and provided with a projecting portion which extends through the opening of the 100 lock member, and a sealing means engaging the projecting portion. 95

2. A trunk lock, comprising a plate member having a keyed lock member hinged thereto and provided with an opening, an 105 escutcheon plate engaged by the lock member and having a projecting post which extends through the lock member opening and is provided with an eye in its outer end portion, and a sealing means extending through 110 the eye.

3. A trunk lock, comprising a plate mem-

ber having a keyed lock member hinged thereto and provided with a projecting lock and an opening between the lock and the hinge connection, an escutcheon plate engaged by the projecting lock and having an outwardly projecting post which extends through the lock member opening and is provided with an eye in its outer end portion, and a sealing wire extending 10 through the eye and having a seal attached to its opposite ends.

4. The combination with a trunk having a lock formed with a hinged and keyed locking member and an escutcheon plate, of a 15 sealing means therefor comprising an eyed

post projecting through an opening formed in the hinged locking member, and a sealing member extending through the eye of the eyed post.

5. The combination with a trunk having 20 a lock formed with a hinged and keyed locking member and an escutcheon plate member engaged thereby, one of said members having an opening and the other member having an eyed post which extends through 25 the opening, and a sealing means extending through the eye of the eyed post.

In testimony whereof, I affix my signature.

GEORGE HENRY WHEARY.
